AUTOMOBILE DOOR LOCKING MEANS

Cecil L. Duquaine, Menominee, Mich.

Application July 3, 1933. Serial No. 678,937

2 Claims. (Cl. 70—74)

This invention relates to a novel single point control multiple acting lock-equipped structure especially, but not necessarily, adapted for simultaneously locking two or more automobile doors.

5 The general object of the invention is to provide a pair of locks of simple construction and arranged in stationary parts of the automobile or other structure, with means whereby the movement of one lock by a key will actuate the other lock.

10 Other features will become more readily apparent from the following description and drawings.

In the drawings:

15 Figure 1 is an elevational view of the body of an automobile with the improved locking means installed therein.

Figure 2 is a horizontal sectional view through the arrangement depicted in Figure 1.

20 Figure 3 is a transverse or vertical sectional view taken approximately on the plane of the line 3—3 of Figure 1.

Figure 4 is an assembly view of an elevational and sectional type showing the mechanical coordination of parts somewhat more in detail.

25 Figure 5 is a view like Figure 4, showing the locking bolts projected to door locking positions.

Figure 6 is a horizontal sectional view taken approximately on the plane of the line 6—6 of

30 Figure 4.

Figure 7 is an elevational view of one of the sliding lock bolt actuating blocks.

Figure 8 is a side view of one of the especially designed locking bolts or pins.

35 In the drawings, the body of the automobile, which is conventional, is distinguished by the numeral 9 and the doors are represented by the numerals 10 and 11. In the arrangement shown, there are four doors, the two rear doors denoted

40 by the numeral 10 and the front doors by the numeral 11. It is evident however that the invention may be adapted to a two door car.

In Figure 1, the numerals 12 designate the vertical styles in which the locking units are installed to obtain the desired double-acting results.

45 Referring now to Figures 4 and 5, it will be seen that there are two companion lock units, which for the sake of convenience are differentiated by the numerals 13 and 14 respectively. These units however, are substantially the same in construction, and a description of one will suffice for both. Each unit comprises a suitably shaped and proportioned casing 15 provided with an appropriate face or cover plate 16.

Slidably mounted for limited reciprocation in the body of the casing is a block 17 which may be conveniently denoted as a slide. The opposite faces of this slide are formed with cut-out portions which define clearance recesses 18. One wall of the recess denoted by the numeral 19 is inturned and formed with a substantially T-shaped grooved 20 which defines a track. This track is adapted to accommodate an inclined cam head 21 formed integrally on the inner end of the projectible and retractile locking bolt or pin 22 (see Figure 8). Each unit is provided with a pair of these locking bolts disposed out of alignment or in the staggered relationship illustrated in Figure 6. The bolts project 70 slidably in horizontal planes through guide collars 23 on the vertical edge portions of the casing.

Obviously, as the block slides up and down, the locking bolts are projected or retracted according to the direction of movement due to the cam 75 co-action between the cam head 21 and the inturned trackways or grooves 20.

The operating means for the slide 17 and the master unit 14 is key-controlled. It comprises a vertical rack bar 24 secured rigidly on one side 80 of the block as shown in Figures 4 and 5 at the left. Meshing with this is a rotatably mounted pinion 25 having a suitable keyhole 26 to accommodate the conventional key (not shown).

The sliding block 17 in the secondary unit 13 85 is arranged in reverse order and travels in a reverse direction to that of the block in the primary unit 14, as is obvious from an inspection of Figures 4 and 5. The movement of the block in the latter unit 13 is attained by way of a flexible operating connection 27 extending through an appropriate protective tube or casing 28. This tubular casing is mounted in the body of the car as illustrated in Figure 3 whereby to transmit the motion from the primary to the 90 secondary sliding block.

95 Thus each unit itself is of a double-acting type and the two units are mechanically co-ordinated to operate in unison and by mounting the units in the standards or stile 12 as shown in Figure 1, 100 and providing appropriate keepers in the doors for the locking bolts, all doors are simultaneously locked or opened as the case may be.

All that is necessary with this arrangement is to close the doors, place the key in the slot or 105 opening 26 of the pinion 25, and turn it in the direction of the arrow shown in Figure 4, thereby bringing about the unified action capable of simultaneously locking the doors.

The gist of the invention is found in the pro-

vision of primary and secondary twin bolt locking units operatively joined together for operation in unison, together with the key-actuated rack and pinion means in the primary unit, serving to permit all doors to be controlled from a single point. Incidentally, whenever it is desired to control the main locking unit from the inside, this is accomplished by providing the same with an inside operating handle 29 as shown in Figure 6.

Novelty is also predicated upon the construction of a twin or duplex locking unit comprising a casing with slidable cam-equipped tracks therein, and a pair of complementary projectible and retractible locking bolts having cam co-acting connection with the cam tracks and suitable means for operating the slide, whether it be a handle 29, rack and pinion means actuated by a key, or the flexible operating connection 27.

20 A careful consideration of the foregoing description in conjunction with the illustrative drawings will enable the reader to obtain a clear understanding of the purpose, features and advantages, the explicit construction, and the invention as hereinafter claimed.

It is to be understood that minor changes in shape, size, relative proportions and materials may be resorted to in practice without departing from the spirit of the invention or the scope of 30 the invention as now claimed.

I claim:

1. A lock of the class described comprising a casing having an opening in one side thereof, a

bolt passing through said opening, the inner end of the bolt being diagonally arranged and having an annular groove therein also diagonally arranged, a reciprocatory member located in the casing and having a recess in one face thereof extending through that side edge thereof which is adjacent the side of the casing having the hole therein, the inner wall of the recess being diagonally arranged and having a T-shaped groove therein for receiving the inner end of the bolt, 85 and means for reciprocating said member for projecting and retracting the bolt.

2. A lock of the class described comprising a casing having an opening in each side edge thereof, with one opening arranged adjacent the front 90 of the casing and the other adjacent the rear of the casing, a block mounted for reciprocatory motion in said casing, said block having recesses in its front and rear faces, said recesses passing through opposite side edges of the block, bolts 95 passing through the openings in the side edges of the casing and extending into said recesses, each bolt having a sloping inner end and provided with an annular groove adjacent said end and also sloping and each recess having a sloping 100 inner wall, the sloping wall of one recess extending in an opposite direction from the sloping wall of the other recess and each of said walls having a T-shaped groove therein for receiving the inner end of a bolt, and means for reciprocating 105 the block.
